WOOD PLANE

Howard H. Benn, Detroit, Mich., assignor to
Catherine V. Pearce, Oak Park, Ill.

Application March 23, 1942, Serial No. 435,790

2 Claims. (Cl. 145—15)

The present invention relates to improvements in wood planes and the like.

One of the objects of the present invention is to provide a wood plane having provisions for facilitating the removal of accumulated shavings.

Another object is to provide an improved cutting blade adjustment mechanism for a wood plane.

A further object is to provide a wood plane having improved means for bevel cutting.

A still further object is to provide novel means for protecting the cutting blade of a plane.

Other objects and advantages residing in the combination, arrangement and construction of parts will more fully appear from a consideration of the following specification and the annexed claims.

In the drawing,

Fig. 1 is a plan view of the improved plane.

Fig. 2 is a side elevational view of Fig. 1, partly shown in vertical cross section.

Fig. 3 is a fragmentary cross sectional view of a portion of Fig. 2 showing the hinged bottom part in a shaving clearing position.

Fig. 4 is a fragmentary side elevational view of a slightly modified form of the invention, and

Fig. 5 is a cross sectional view taken on line V—V of Fig. 4.

Referring to the drawing, the principles of the present invention are disclosed in connection with a cast plane body 10 having a rear portion 12, and a front portion 14 having vertical side portions 16 and 18. Generally speaking, the improvements of the present invention in plane construction are subject to being embodied in planes of many shapes, sizes and types of constructions, and for this reason it is not my desire to limit myself to any specific type of plane or method of fabrication.

Threaded in the post 20 is a blade adjustment screw 22 having a knurled head 24. The opposite end of the screw 22 carries a T-shaped member 26 which rotates in a similarly shaped slot 28 in the cutting blade 30. It will be observed that the longitudinal axis of the adjustment screw 22 and cutting blade 30 may be in offset parallel planes or in angularly disposed planes without affecting the operative relation between the T-shaped member 26 and the slot 28.

The blade 30 is supported for sliding adjustment movement on the inclined portion 32, being held by a spring plate 34, and a coil spring 36 compresses by tightening the handle portion

38, having a threaded shaft 40 operating in the threaded hole 42 in the body 10 of the plane. The slot 44 in the blade 30 permits adjustment of the blade with the members just described holding the blade firmly against the surface 32. In using the plane, one hand of the operator grips the knob handle 38 and the other the rear handle 46.

A structure for facilitating the removal of accumulated shavings comprises a hinged bottom portion generally designated by reference character 48, having a main portion 50 which functions as a continuation of the bottom portion 52 of the main body 10. The bottom portion 50 is illustrated as having upright portions 54 and 56, having holes 58 to receive the shaft 60, suitably supported at opposite ends in the sides 16 and 18. As more clearly shown in Fig. 1, the bottom portion 50 is supported in an opening between the sides 16 and 18, and functions and corresponds to the lower portion of a conventional plane which is usually an integral part of the plane body in lieu of being hinged as herein disclosed. A spring 62 upon the shaft 60 has one end anchored with respect to the bottom portion 50 and the other end 64 anchored in an opening 66 in the side 18. The spring continuously urges the bottom 50 into engagement with the stop pins 64 and 66 to position the bottom 30 50 in the same plane as the bottom 52 of the main body portion 10 of the plane. The tension of the spring 62 is such as to maintain the bottom portion 50 in the position shown in Fig. 2 throughout the normal use of the plane. It will be noted that the rear end 68 of the bottom 50 terminates short of the gap 70 in the bottom of the plane through which the cutting blade 30 is projected in the usual manner. In the event of an accumulation of shavings in the gap 70, upward pressure applied upon the front portion 72 will cause hinging of the bottom portion 50 as indicated in the dotted outline in Fig. 3. This hinging operation will provide a convenient clearing of all accumulated chips and shavings forward of the cutting blade and usually occurring in the gap 70.

The pivotal mounting of the bottom portion 50 affords a very convenient method of protecting the cutting edge of the blade 30 when the plane is not being used. In the illustrated form of the invention this has been accomplished by providing a threaded stud 72 on the upper surface of the bottom portion 50 to receive a clamping nut 74 having a knurled head 76. The nut 55 74 is adapted to hold in positions of adjustment

a plate 78, having a slot 80 for clearing the stud 72. Integral with the plate 78 are upright portions 82 which may be engaged by the fingers to slide the plate 78 along on the upper surface of the bottom portion 50. In Fig. 3 the bottom 50 is shown sufficiently tilted to enable the plate 78 to be advanced along the surface of the plate 50 to a point where the end of the plate 78 will be disposed below the pins 64 and 66 and engage the blade 30 above its cutting edge. Through this arrangement the plate 78 may be selectively positioned to hold the bottom member 50 in the position shown in Fig. 3 protecting the cutting blade 30 and permitting the plane to be supported in an upright position without dulling the cutting blade. It will be understood that the clamp nut 74 is tightened and loosened to maintain the plate 78 in different positions of adjustment.

In Fig. 4 is shown a slightly modified form of the invention in which the bottom member 50', hingedly supported upon the shaft 60', has a width corresponding to the width of the main body of the plane and when in operative position is urged upwardly by the spring 62' into the recess 82 defined in the side members 16' and 18'. The recesses 82 in this manner perform the function of the positioning pins 64 and 66 in the form of the invention illustrated in Figs. 1 to 3, inclusive.

Where it is desired to cut a slight bevel with a plane, this can be done by supporting the cutting blade 28' of Figs. 4 and 5 upon a pair of slightly tapered plates 84 and 86. As the taper of the plates 84 and 86 is equal but opposite when both of the plates are used as shown in Fig. 5, then the cutting blade 28' is supported level. However, by removing either one or the other of the plates 84 and 86, a bevel in one direction or the other will be cut by the blade 28' for the reason that the blade 28' will assume a slight angle under the pressure of the spring 36' acting through the handle 38' against the clamping blade 34'. The edges of the wedge or tapered plates 84 and 86 are slightly rounded so as to permit the tilting of these blades between the sides 16' and 18' of the plane.

To complete my improved tool provisions are made for working in places where a full stroke of the plane is not possible, as for example, a corner. At the rear surface 86 screws 88 hold the cutting blade 90 in position. As shown, the projecting sharpened edge 92 will be received in the recess 94 with the blade inverted in an inoperative position. Preferably the holes in the blade 90 are slightly oversized to permit the screw 86 to clamp the blade 90 in different vertical positions of adjustment.

Having thus described my invention what I desire to secure by Letters Patent and claim is:

1. A wood plane comprising a main body portion provided with a work engaging bottom portion and having a cutting blade receiving support, said body being provided with an opening through the bottom thereof in front of the cutting blade receiving support, a cutting blade mounted on said support and projecting through the opening, a second bottom portion pivotally supported by the main body portion at the forward end thereof with the rear end terminating sufficiently in front of the cutting blade to provide cutting clearance therefor and said second bottom portion being downwardly swingable at its rear end to clear the cutting blade, yieldable means normally swinging said second bottom portion upwardly to lie in a plane with the work engaging bottom portion, stop means limiting upward movement of the swinging end of said second body portion, and means insertable between the swinging end and said stop means and lowering the swingable end sufficiently to interpose said end as a protection for the cutting edge of the blade.

2. A wood plane comprising a main body portion provided with a work engaging bottom portion and having a cutting blade receiving support, said body being provided with an opening through the bottom thereof in front of the cutting blade receiving support, a cutting blade mounted on said support and projecting through the opening, a second bottom portion pivotally supported by the main body portion at the forward end thereof with the rear end terminating sufficiently in front of the cutting blade to provide cutting clearance therefor and said second bottom portion being downwardly swingable at its rear end to clear the cutting blade, yieldable means normally swinging said second bottom portion upwardly to lie in a plane with the work engaging bottom portion, stop means normally engaged by the swinging end of said second bottom portion positioning said second portion in a plane with the work engaging bottom portion of the main body, a plate slidably mounted on said second bottom portion movable to a position interposed between the swinging end of said second portion and the stop and in engagement with the blade above the cutting edge thereof and to a second position withdrawn from contact with said stop means, and means to hold said sliding plate in each of its adjusted positions.

HOWARD H. BENN.
